UNITED STATES PATENT OFFICE.

ROBERT C. MATHEWS, OF WYOMING, NEW JERSEY, ASSIGNOR TO WESTERN ELECTRIC COMPANY, INCORPORATED, OF NEW YORK, N. Y., A CORPORATION OF NEW YORK.

TWO-WAY RADIO SIGNALING SYSTEM.

Application filed March 11, 1924. Serial No. 698,353.

This invention relates to two-way radio signaling systems and particularly to a combined transmitting and receiving station of such a system.

5 Warrant for the term "a combined transmitting and receiving station", as distinguished from a term suggesting separate functions and structures for the component transmitting and receiving circuits, is found 10 in the close physical relationship between such circuits at a station so designated. There may be a common antenna for the two circuits; the circuit may be coincident at some other point; or the circuits may be entirely separate, but in close proximity to each other. The arrangements at such stations are characterized by a condition favorable to singing or at least to the production of side tone in the receiver from the local transmitter. This condition is much more critical in 15 radiant energy systems than in similar systems utilizing lower frequency since in the former, on account of the high frequencies used, and distributed capacity as well as other 20 casual and unavoidable capacity is effective as an impedance element whereas in the latter it is negligible. Moreover in radio systems, as contrasted with wire systems, considerably 25 larger amounts of energy are necessarily required in carrying out the transmitting function as compared with the amount of energy required to carry out the receiving function, thereby increasing the liability of singing or 30 side tone production.

35 An object of the invention is to avoid singing or the production of side tone in a receiving circuit of such a combined radio transmitting and receiving station by energy from the local transmitter.

40 Among the means that have heretofore been used in the attainment of the above object there are included commutation means, and specifically, relay operated switches to render the transmitting and receiving circuits alternately operative. In one specific form of 45 system embodying such a commutation means a portion of the outgoing energy, and specifically a portion of the sound or other form of energy used for signaling transmission, is used to energize the relays to actuate the switches in one phase of their movement,

biasing means being used to restore them to their initial conditions.

A difficulty which is inherent in the commutation arrangement last described is that 55 an appreciable time is required, on account of the mechanical inertia of the moving parts of the relay, etc., to complete the reorganization of the circuits preparatory to their use for a new phase of operation. Since in a 60 system of this kind in which the circuits are normally biased to the receiving condition, the beginning of transmission from the signaling source is coincident with the initiation 65 of the switching operations, the completion of these operations does not occur soon enough to provide for the radiation of the first part of the signal, that is, the signal transmission is "clipped".

A further object of the invention accord- 70 ingly is to control the responsiveness of the receiving circuit and the operation of the transmitting circuit at such a station directly by signaling energy and without "clipping" 75 at the beginning of transmission.

The above stated objects are realized, for 80 example, in a voice controlled two-way radio station in general resembling that above described. However, in the circuit of the present invention the relays for effecting the desired reorganization are in a separate control circuit branched from the main transmitting circuit, and the main transmitting circuit includes a delay circuit anterior to the first 85 relay affected element. This delay circuit in effect stores the signals until the relay actuated switches have prepared the transmitting circuit for transmission of the signals into space.

In an arrangement in which the low fre- 90 quency portions of the transmitting and receiving circuits are connected, as is the case for example, where each is joined to a common subscriber's telephone circuit, the received low frequency current, to the extent 95 that it could flow into the transmitting circuit at the junction point, would function in all respects like outgoing signaling current. It would accordingly tend to cause, through the transmission control circuit, a 100 reorganization of the circuits as a whole in such a manner as to render them operative

for receiving. This result would tend to be brought about whether or not the delay circuit principle is used in operating the transmitting circuit.

5 It is a still further object of the invention to avoid the result described in the foregoing paragraph.

This object is achieved by causing the normally received energy operating through a 10 receiver control circuit to render the transmitting control circuit inoperative.

The delay circuit principle is used in a receiving circuit of this invention to insure that the operation, whereby the transmitting 15 control circuit is rendered inoperative, will be completed before the received signal wave has progressed to the point of connection of the circuits. The use of delay circuits in both the transmitting and receiving circuits of 20 radio systems, in combination with the various features described above, results in a close approach to the conditions of operation in ordinary subscriber station circuits in wire 25 telephony. The particular means of the invention are sufficiently effective for their respective purposes as to permit the use of the same carrier frequencies for both systems of transmission.

The delay circuits may be loaded circuits 30 of any type, for example, a conventional wave filter which consists of a plurality of sections the number and constants of which are designed to give the requisite time lag.

The menace of side tone interference in 35 the receiving circuit by energy from the local transmitter is reduced by the above described operations whereby the transmitting and receiving circuits are alternately rendered operative. This result may be accomplished by 40 affecting the connections between the antennæ (or the antenna if a single antenna is used in common for the two circuits) and the remaining portions of the transmitting and receiving circuits. It may be alternatively 45 or additionally accomplished by affecting the transmitting and receiving circuits elsewhere than at the antennæ. For example, the transmitting circuit which is normally inoperative may be rendered operative by increasing the grid polarizing potential of the 50 grid of a three element repeating tube in series in the transmitting circuit to a value sufficient to make the space circuit conductive.

This invention includes a particular means 55 for changing the grid polarizing potential so as to prevent the generation of transients in the circuits, that would otherwise be set up if the customary relay actuated switches were used to produce variation of the grid potential, because of the rapid rate at which this 60 variation would take place. Such transients are detrimental to the best operation of the system hence the feature of the invention whereby they are prevented is important.

65 This particular means involves the use of a

space discharge tube repeater having its tubes connected in the so-called push-pull or balanced relation and the common portion of its grid-filament circuits arranged to effect the desired grid potential variation.

70 The invention will be better understood by reference to the following specification and accompanying drawings in which:

Fig. 1 represents in diagrammatic form the 75 circuits of a complete two-way radio station of the invention;

Fig. 2 represents a circuit which may be substituted for that portion of Fig. 1 between lines X—X and Y—Y;

Fig. 3 represents a circuit which may be 80 substituted for that portion of the circuit of Fig. 1, or of Fig. 1 varied in accordance with Fig. 2, at the right of points A, B, C, D, E and F, the correspondence of letters in Figs. 1 and 3 indicating the manner of substitution;

Fig. 4 represents an arrangement alternative 85 to that of Fig. 3 and which may be similarly substituted in the system of Fig. 1; and

90 Fig. 5 indicates a form of delay circuit which may be substituted for the blocks so marked in the systems of Figs. 1 and 2.

In the particular systems illustrated by 95 Figs. 1 and 2, a common antenna AN is used for the transmitting and receiving circuits, the terminus of the transmitting circuit being shown at the left of the antenna and that of the receiving circuit at the right. The antenna is connected to one circuit or the other 100 according to the position of the switch 1 which is normally held in the receive position but which is capable of being actuated by relay 2 to take the transmit position. This switch is illustrated as in the receive position, to which it is normally biased by means not shown. The other switches 3, 5, 7 and 9 are similarly biased to their normally inoperative positions illustrated.

105 Disregarding for the moment the control 110 circuits including the relays and their related switches, the transmitting circuit comprises, in substantially the order given, the low frequency line L, the amplifier A, the delay circuit DC, the modulator M, the oscillator O, the balanced amplifier BA and the antenna AN, by which combination the signals from low frequency line L are amplified and are then used to modulate the current 115 from oscillator O, after which the signal modulated wave is amplified and radiated. These functions and elements for performing them are each conventional in carrier systems and do not require further description.

120 The delay circuit may be simply a loaded transmission line designed to give a uniform retardation to the various frequency components making up the signaling current. The delay circuit illustrated in Fig. 5, which 125 is effective for this purpose, consists of series 130

inductances and shunt capacities. It may be a low pass filter of the type disclosed at 1st in Fig. 11 of United States patent to Campbell, No. 1,227,114 granted May 22, 1917, although 5 a delay circuit is not required to have the characteristics of a filter. Delay circuits per se and the specific form of Fig. 5 are the inventions of H. D. Arnold and are disclosed in his United States Patent 1,565,302, December 10, 1925.

Delay circuits of the types disclosed are forms of loaded lines having series inductances and shunt capacities. The manner in 15 which a loaded line acts to slow down transmission is discussed in U. S. patent to Pupin 652,231, June 19, 1900, to which reference may be made for an explanation of their operation.

A physical explanation of a phenomenon 20 like this is sometimes more satisfactory at least to some persons, than a purely mathematical method of proof which the method of the Pupin patent approximates. In this connection it should be remembered that a 25 time delay in its broadest sense means merely that the speed of transmission is finite rather than infinite and a necessary incident of the propagation of a wave at a definite velocity is, almost by definition, a progressive change of phase throughout the 30 length of the circuit. Accordingly, a circuit whose operation is characterized by such change of phase is, to that extent, a delay circuit. Artificial networks, whose sections 35 are similar to those of commercial filters, operate in this manner within their transmission ranges. A physical, as distinguished from a mathematical, explanation is given 40 in a paper entitled "Physical theory of the electric wave-filter" by G. A. Campbell which appears in the Bell System Technical Journal for November, 1922. See particularly the second numbered paragraph on page 10.

That there must be this progressive change 45 of phase from section to section of a filter-simulating network for each frequency within the transmission range may be explained very simply, and more briefly than in Campbell's paper above cited. This explanation is in accordance with a method 50 which has heretofore been used only with reference to mechanical wave filters, but it is equally applicable to electrical filter-simulating networks.

55 Assume the most general case of such network having the characteristics of a band filter, of which the network of Fig. 5 which simulates a low pass filter is a limiting case. Assume also that there is no resistance in the 60 network. Consider first the frequency at the lower cut-off. At this frequency the series inductance and shunt capacity of each section are in resonance and the current is therefore not attenuated. The reactions 65 from the shunt capacities are not effective on

account of the quadrature relation of line and shunt currents. There is, therefore, no periodic interchange of energy between the series and shunt elements, so that the "propagation velocity" is infinite. 70

Now consider a component within the transmission range, but at a higher frequency than the lower cut-off frequency. The kinetic reaction of the mass element (series inductance) is greater than the potential reaction of the elasticity element (shunt capacity) so that there is no longer resonance of the two elements. This condition results in a phase shift in the series section, as compared with the condition at the lower cut-off frequency, and therefore the series and shunt currents are no longer in phase quadrature, so that the shunt capacity lends a portion of its reaction to assist that of the series capacity to preserve the necessary equality of reactions, which equality indicates a condition of non-attenuation. 75 80 85

This phase shift is repeated for each section. A different shift increasing with the frequency, occurs for each frequency within the range. At a certain critical frequency there is a 180° phase shift per section. This corresponds to the condition of maximum effectiveness of the shunt elasticity in neutralizing the effect of increasing mass reaction. Accordingly, currents having frequencies greater than this value must work against an excess mass reaction and are therefore attenuated. This frequency therefore corresponds to the upper cut-off. 90 95 100

Currents having frequencies below the lower cut-off are similarly attenuated as could easily be demonstrated by a complementary mode of reasoning. Currents having frequencies below the lower cut-off have zero phase shift and their "propagation velocities" are therefore infinite. For currents having frequencies above the upper cut-off the phase shifts remain at 180° so that the velocities of propagation are finite, but obviously on account of the attenuation characteristic the network cannot be used as a delay circuit for such currents. The delay, of course, is greater for frequencies near the upper cut-off than for those near the lower cut-off. A filter-simulating network can therefore be used as a delay circuit for frequencies within its transmission range. 105 110 115

When account is taken of the fact that the condition of increased phase shift corresponds to a condition of increased frequency and therefore of a decreased period, it is evident that the delay is substantially the same for all frequencies in the transmission range. The delay, of course, is a 120 function of the number of sections. For example, if there was a phase shift of 180° per section for a 500 cycle wave, 100 sections would be required to cause a delay of a tenth of a second. 125 130

The balanced amplifier is of the type disclosed in United States patent to Colpitts No. 1,128,292, granted February 16, 1915. When the switch 5 is closed, as during the receiving phase of operation at the station, the negative potential of battery 11 is added to that of battery 12 to make the amplifier inoperative for transmission. When the switch is opened, by relay 6, the amplifier is made operative.

The receiving circuit comprises the antenna AN, the detector-amplifier DA, the delay circuit DC₁, and low frequency line L, by means of which received signal waves are amplified and detected to reproduce a signal frequency current which is transmitted through the delay circuit to the low frequency line. The delay circuit may be like or unlike that used in the transmission circuit. The low frequency portions of the transmitting and receiving circuits are connected to the common line L through a three winding transformer T and network N by means of which the connection may be made substantially conjugate.

In the two-way system of Fig. 1 the provision of a single antenna connected alternately to the transmitting and receiving circuits insures that these circuits are alternately operative, and hence that the condition of the circuits as a whole is unfavorable to singing. The signal control means for accomplishing this and similar functions, will now be described.

Antenna AN is switched to its transmit position by relay 2 which actuates switch 1. Relay 2 is in the transmitting control circuit together with relays 4 and 6 which similarly actuate switches 3 and 5. Although these relays are shown connected in series they may equally well be connected in parallel. The use of the additional relay actuated switches further insures against singing. Switch 3, for instance, is normally biased to the circuit closing position and is actuated to the circuit open position coincidently with the actuation of switch 1, to produce a secondary break in the receiving circuit. Instead of producing a break this switch may be used in an obvious manner to short circuit the receiving circuit. Switch 5 is normally biased to circuit closed position to maintain the balanced amplifier and oscillator in the transmitting circuit in an inoperative condition and is actuated to circuit open position coincidently with the actuation of switches 1 and 3 to increase the grid potentials and accordingly to make the transmitting circuit operative.

Relays 2, 4 and 6 are included in a circuit branched from the signal transmission circuit and are energized by the operation of the signal current after rectification in the rectifying device AR which ordinarily, although not necessarily, would amplify as well as rectify. Additional amplification may be

obtained by separate stages of amplifiers if desired. The delay circuit DC insures that the various switching functions are completed and accordingly, the circuit as a whole prepared for transmission, in time to permit the first part of the signal to be transmitted and radiated from the antenna. Its use accordingly prevents "clipping" of the transmitted signal.

The balanced amplifier having the switch 5 in the common portion of the grid-filament circuits has the important function of preventing the setting up of transients that would otherwise result from the sudden change of grid potential. These transients would tend to affect the receiving circuit in much the same way as static impulses incident on the receiving circuit. Although there is no conductive connection between the high frequency portions of the transmitting and receiving circuit, these transient impulses might easily have sufficient intensity to inductively affect the receiving circuit. An important advantage in the case of large power stations, resulting from switching by shutting off the space current in the power amplifier is the saving in transmitted power that is affected during the time when signal transmission is not taking place.

In the circuits of Fig. 1 as so far described the connection between the low frequency portions of the transmitting and receiving circuits results in a difficulty not present where such circuits are separate, that it, it provides a path for the detected low frequency current to enter the transmitting circuit. The balanced transformer and network is not effective under practical conditions to prevent the flow of a quantity of this energy sufficient to actuate the transmitting relays to open the receiving circuit. The effect would immediately cease when the switches have been actuated, whereupon the biasing means would restore the circuits to their initial condition. This cycle of operation would be repeated at a periodicity determined by the natural period of mechanical movement of the switches.

This effect is avoided in the present invention by causing a portion of the detected low frequency, after amplification and rectification in device AR, to actuate switch 7 through relay 8. This operation renders inoperative the transmitting circuit and particularly the control circuit branched therefrom. The current which actuates switch 7 through relay 8 also actuates switch 9 through series relay 10 to remove a short circuit from the low frequency portion of the receiving circuit. This switch is normally biased to its closed position and comprises one of the several elements which cooperate to prevent singing or interference during transmission.

The delay circuit DC₁ functions in a manner similar to the delay circuit in the trans-

mitting circuit to insure that the received signal is not "clipped" during the operation of switch 9. It also functions to prevent the operation of switches 1, 3 and 5, by received 5 energy before switch 7 has had time to operate.

Fig. 2 illustrates a circuit which may be substituted for that included between lines X—X and Y—Y. The elements having similar functions are identified in the same manner as in Fig. 1. The modified arrangement differs functionally from that of Fig. 1 only in that the transmitting circuit is made operative by effectively connecting the carrier oscillator to the modulator, instead of affecting the impedance of the amplifier. Specifically the step is accomplished by removing the short circuit from the oscillator O, which normally exists by reason of switch 5, by 10 means of relay actuated switch 5. Amplifier A₁ may be used, if necessary, to amplify the modulated carrier current. Although this amplifier may be of the balanced type as in Fig. 1, the reasons urging its use in that circuit are not here present, and a single tube amplifier would be practically as effective.

Figs. 3 and 4 illustrate modifications of similarly labeled portions of the circuits of Fig. 1. In the arrangement of Fig. 3, although the antenna is not alternately connected to the transmitting and receiving circuits, it is nevertheless alternately put in energy transfer relation to said respective circuits by the switching means illustrated. That is, switch 1 is opened by relay 2 to remove a short circuit on the coil 13 in the antenna circuit which coil functions during transmission as the secondary of the oscillation transformer. The receiving circuit is effectively uncoupled from the antenna by switch 3 and relay 4. An advantage possessed by the circuit of Fig. 3 over that of Fig. 1 is that the two operations take relatively less time for their completion since the antenna is made operative for transmission by the opening, instead of the closing, of a switch. As a result the problem of designing a delay circuit having the requisite time lag is more simply and less expensively met.

The arrangement of Fig. 4 is alternative to that of Fig. 3 and the corresponding portions of Fig. 1. The figure illustrates the application of the principle of the arrangement of Fig. 3 to the case of separate transmitting and receiving antennæ. The receiving antenna AN₁ may be a loop as illustrated or any other conventional form of receiving antenna. The directional selective properties of a receiving loop makes it possible to secure additional discrimination from locally transmitted energy by its use in this circuit. The means for making the antenna effective for transmission differs from that of Fig. 3 in that, instead of effectively coupling the antenna to the transmitting circuit, the switch

1 and relay 2 effect a change in the resonant frequency of the antenna from a condition unfavorable to a condition favorable to transmission.

In the arrangement of Fig. 1 modified by the substitution of the circuits of Fig. 2, the switch 1 has additional advantages not resulting from the use of the circuits of Fig. 1 unchanged. These additional advantages result from the fact that in such a modified system the power amplifier is not effectively removed from the circuit as in Fig. 1. In powerful stations in which the ratio of transmitted to received power is enormous, the incidental disturbances in the power amplifier would tend to set up transients in the outgoing antenna which would seriously affect incoming transmission. This is avoided by switch 1 which disconnects the power amplifier from the antenna during reception. The corresponding means in Figs. 3 and 4 are similarly effective to prevent this particular type of interference.

The novel features believed to be inherent in this invention are disclosed in the appended claims.

What is claimed is:

1. A signaling circuit comprising a source of modulating waves, means utilizing the waves from said source for producing a signal modulated wave, and means for transmitting the elements of said modulated wave at equal predetermined intervals of time after the production of corresponding elements of the modulating wave, said last mentioned means comprising a delay circuit between said source and said first mentioned means.

2. A two-way radio signaling station comprising a normally operative receiving circuit, a normally inoperative transmitting circuit, means operative only during the production of a signal modulated wave for rendering said circuits respectively inoperative and operative, and means for preventing the impression of said wave on the transmitting circuit during the operation of said means.

3. A two-way radio signaling station comprising a normally inoperative transmitting circuit, means for generating a signal modulated carrier wave, means operative only during the production of said wave for making said circuit operative, and means for preventing the impression of said wave on said circuit during the operation of said second mentioned means.

4. A two-way radio signaling station comprising a normally inoperative transmitting circuit, means for producing a signal modulated wave, means operative only during the production of said wave for rendering said circuit operative, and automatic means for preventing the clipping of the signal transmission during the operation of said second mentioned means.

5. A two-way radio signaling station comprising a transmission circuit, means normally making said circuit inoperative, means for generating a signal modulated wave, means operative only during said generation and dependent thereon for maintaining said circuit in an operative condition, and means for preventing the clipping of the signal transmission during the operation of said 10 third-mentioned means.

6. In combination, a source of signal waves, means for modulating high frequency carrier waves in accordance with said signal waves, a radio transmission circuit, means 15 for rendering at least one portion of said circuit at times inoperative for transmission, means for rendering said portion at other times operative for transmission, and means whereby each element of said modulated 20 wave is incident on said portion nearest to said source a predetermined definite time after the generation of said signal waves.

7. In combination, means for generating a signal modulated current, a circuit for translating said current into ether waves, means for rendering at least one portion of said circuit normally inoperative for transmission, means operative only during said generation and dependent thereon for making said 25 circuit operative, and automatic means whereby said generated wave is incident on said portion nearest to the generating means only after all of said portions have been made 30 operative for transmission.

8. In combination, means for generating a signal modulated current, a circuit for translating said current into ether waves, means normally rendering at least one portion of said circuit inoperative for transmission, signal-actuated means for making and 40 maintaining said portions operative during said generation, and a delay circuit in said circuit for preventing the impression of said waves on said portions until they have been 45 made operative for transmission.

9. In combination a source of signal current, a source of carrier frequency current, means for modulating said carrier current in accordance with said signal current, a circuit 50 for translating said modulated current into ether waves, means normally rendering at least a portion of said circuit inoperative for transmission, means actuated by said signal current for making and maintaining said 55 portions of the circuit operative, and a delay circuit for preventing modulation of the carrier current by the signal current before said portions have been made operative.

10. In combination, a source of signal current, a source of carrier frequency current, means for modulating said carrier current in accordance with said signal current, a circuit 60 for translating said modulated current into ether waves, means normally rendering at least one portion of said circuit inoperative 65

for transmission, a relay-containing circuit connected to said signal current source for rendering said portions operative during signal current generation, and a delay circuit between said signal current source and said 70 modulator for preventing modulation until said portions have been made operative.

11. In combination a source of signaling current, a source of carrier current, means for modulating said carrier current in accordance 75 with said signaling current, radiating means, a transmission circuit connecting said modulating and radiating means, means normally rendering said circuit inoperative for transmission, means normally rendering 80 said radiating means inoperative for radiating, means responsive to the signal current for making said circuit and radiating means operative, and a delay circuit for preventing a clipping of the signal while said last 85 mentioned means is being operated.

12. In combination, a signal current source, a carrier current source, a radiating means, means for generating and transmitting to said radiating means a signal modulated carrier current wave and including a three-element electric discharge device having anode, cathode, and an impedance controlling element, means for normally affecting the potential of the impedance controlling element to make the electric discharge device inoperative, means for at times affecting the potential of said impedance controlling element in a different sense to make said 90 electric discharge device operative, and means whereby a change of potential of said impedance controlling element is effected independent of the production of transients in the output circuit of said electric discharge means. 95

13. The circuit specified in claim 12 in which the electric discharge means comprises balanced three-element electric discharge devices each having a cathode, an anode, and an impedance controlling grid, and in which the means affecting the impedance controlling grid operates on the common cathode-grid circuit. 100

14. In combination a signal current source, a carrier current source, means for modulating said carrier current in accordance with the signal, radiating means, a transmission circuit between the modulator and radiating means and including a thermionic discharge amplifier, comprising a cathode, an anode, and an impedance controlling grid, means normally impressing a blocking potential on the grid of said amplifier, means for at times removing the blocking potential from said grid, and means for preventing the production of transients in the output circuit of said amplifier when the potential of its grid is changed. 115

15. The circuit specified in claim 14 in which the amplifier comprises two thermionic 120

- electric discharge devices each having a cathode, an anode, and an impedance controlling grid, the grid-cathode paths for the two devices having portions in common and 6 other portions individual to each device and in which the means for inserting and removing the blocking potential operates on the common portions of the grid-cathode paths. 16. In combination a signal current source, 10 a carrier current source, means for modulating said carrier current in accordance with the signal current, radiating means, a transmission circuit between the modulator and radiating means and including an electric 15 discharge amplifier including a cathode, an anode and an impedance controlling grid, means normally impressing a blocking potential on the grid of said amplifier, means responsive to the signal current for removing 20 the blocking potential from the grid of said amplifier, said amplifier blocking and removing means including a means for preventing the production of transients in the output circuit of the amplifier by a change of grid potential. 25
17. The circuit specified in claim 16 but including additionally a delay circuit between the signal current source and the modulator for preventing the production of the modulated carrier current until the blocking potential has been removed from the amplifier grid. 30
18. The circuit specified in claim 17 including a delay circuit between the signal current source and the modulator for preventing the production of the modulated carrier current until the blocking potential has been removed from the amplifier grid, and in which the amplifier comprises a pair of three-element 35 electric discharge devices in push-pull relation, the means for impressing and removing the blocking potential being operated on the common portions of the grid-cathode paths of the two devices. 40
19. A two-way radio signaling station comprising in combination a signal current source, a carrier current source, modulating means for said currents, radiating means, a transmission circuit connecting said modulating means and radiating means, a low frequency circuit connecting said signal current source and modulating means, a receiving circuit including a demodulator, a second low frequency circuit connected to said demodulator, individual circuit closing means normally biased to respectively render said transmitting circuit inoperative, to render said second low frequency circuit inoperative for transmission, to render said receiving circuit operative for reception, and to connect said radiating means in energy transfer relation to said receiving circuit, a signal responsive means operating on certain of said circuit closing means to render said transmission circuit operative for transmission, to 45
- render said receiving circuit inoperative for reception, and to connect said radiating means in energy transfer relation to said transmission circuit, and means responsive to the demodulated low frequency current 70 for operating on other of said circuit closing means to render said second low frequency circuit operative for transmission. 75
20. A two-way radio signaling system comprising in combination a low frequency line, a common radiating and receiving means, a transmitting and a receiving circuit connecting said line and radiating means, said transmitting circuit comprising a low frequency portion, a carrier current source, a modulating means and a power amplifier, and said receiving circuit including a demodulator and high and low frequency portions, separate circuit closing means normally biased to render the amplifier and the low frequency portion 80 of the receiving circuit inoperative for current transmission, to render the high frequency portion of the receiving circuit operative for reception, and to connect the common radiating means to the receiving circuit, a transmission control circuit branched from the low frequency portion of the transmitting circuit and including relays in energy transfer relation to the circuit closing means 85 associated with the amplifier, radiating means and high frequency portion of the receiving circuit, whereby said circuit closing means are operated responsively to said signal current, a receiver control circuit branched from the low frequency portion of the receiving 90 circuit and including relays in energy transfer relation to the circuit closing means associated with the low frequency portion of the receiver circuit, a circuit closer in said transmission control circuit normally biased 95 to circuit closing position, and a second relay in said receiver control circuit, whereby the circuit closer associated with the low frequency portion of the receiving circuit and the circuit closer in the transmission control circuit are actuated responsively to low frequency demodulated current. 100
21. The circuit of claim 20 including additionally a delay circuit between the point of connection of the transmission control circuit to the low frequency portion of the transmitting circuit and the modulator, for preventing the clipping of the transmitted signal during the operation of the transmission control circuit, and a delay circuit between the point of connection of the receiving control circuit to the receiver circuit and the circuit closer in the low frequency portion of the receiving circuit, for actuating said last mentioned circuit closer and for making inoperative the transmission control circuit before the demodulated current is impressed upon the low frequency portion of the receiving circuit. 115
22. In a two-way radio signaling system, a 120
- 125
- 130
- 135

transmission circuit comprising a signal current source, a carrier current source, means for modulating said carrier current in accordance with said signal current and a power amplifier, a receiving circuit, a common antenna, means normally biased to connect said antenna in energy transfer relation to said receiving circuit, means normally biased to disconnect said carrier current source from 10 energy transfer relation to said modulating means, and means for actuating said normally biased means to respectively change the connection of said antenna from the receiving circuit to the transmitting circuit and to connect said carrier current source in energy transfer relation to said modulating means.

23. In a two-way radio signaling system, a transmission circuit comprising a signal source, a carrier current source, means for 20 modulating said carrier current in accordance with said signal current and a power amplifier, a receiving circuit, a common antenna, means normally biased to conductively connect said antenna exclusively to said receiving circuit, means normally biased to disconnect 25

said carrier current source from energy transfer relation to said modulating means, and signal responsive means for actuating said normally biased means respectively to conductively connect the antenna exclusively to the 30 transmitting circuit and to connect said carrier current source in said energy transfer relation to said modulating means.

24. In a radio system for transmitting and receiving signal modulated waves, a normally inoperative transmitting circuit, a normally operative receiving circuit, said circuits being coupled to a low frequency line, an auxiliary circuit arranged to control said transmitting and receiving circuits, said auxiliary 40 circuit being effective to open said receiving circuit prior to the transmission of energy from said transmitting circuit and to stop transmission of energy from said transmitting circuit prior to the transmitting of signal 45 waves to said low frequency line.

In witness whereof, I hereunto subscribe my name this 4th day of March, A. D. 1924.

ROBERT C. MATHES.
